UNITED STATES PATENT OFFICE.

LOUIS F. DIETER, OF BUFFALO, NEW YORK.

METHOD OF AND MEANS FOR ROLLING OR FORMING CAR-WHEELS OR OTHER CIRCULAR BODIES.

1,243,052.

Specification of Letters Patent. Patented Oct. 16, 1917.

Original application filed June 15, 1911, Serial No. 633,343. Divided and this application filed November 20, 1916. Serial No. 132,372.

To all whom it may concern:

Be it known that I, LOUIS F. DIETER, a citizen of the United States, residing at Buffalo, in the county of Erie and State of New York, have invented novel and useful Methods of and Means for Rolling or Forming Car-Wheels or other Circular Bodies, of which the following is a specification, accompanied by three sheets of drawings.

10 The features of my invention claimed herein are a part of the invention of my original application filed June 15, 1911, Serial No. 633,343, which original application, in accordance with requirements of the Patent Office, has been divided. This application is a division from said original application and, the parts of an apparatus or mill shown in the accompanying drawings are illustrative of parts of my said original

20 application.

The subject matter of the present invention is also described in and certain features of the invention herein described, but not herein claimed, are claimed in my application for patent filed June 15, 1911, Serial No. 633,343, allowed January 23, 1917, of which this application is a division, and this invention is also described or partly described in and certain features thereof herein described, but not herein claimed, are claimed in the following co-pending applications filed by me, viz: Application for patent filed October 10, 1916, Serial No. 124,921; application for patent filed November 22, 1916, Serial No. 132,815, and application for patent filed January 10, 1917, Serial No. 141,558.

This invention relates to the manufacture of car wheels, disk-wheels, or other circular bodies in an economical, commercial, expeditious and efficacious manner, whereby the whole car wheel, disk-wheel, or other circular body may be completely rolled or formed from a properly heated ingot, bloom, blank, or other work-piece, including the forming, at the opposite sides of the work-piece, of a preliminary bore, or a part or parts thereof, in a simple and thoroughly practicable manner with the same heat and before the finished dished or undished wheel, or other finished body, as the case may be, is removed from the apparatus or mill, while at the same time securing a uniform and maximum density and homogeneity in the

metal which contributes materially to the strength and durability thereof (all of which is fully described in my said original application) and, this said invention has particular reference to novel method of and means for supporting the work-piece and for cooling the piercers or work-supporting centers or work-supporting means and work-supporting heads which support the work-piece in an apparatus or mill while the work-piece is being rolled or otherwise operated upon; said method of and means for cooling being absolutely necessary in the continuous operation of an apparatus or mill such for instance as herein described for completely and continually rolling or forming car wheels, disk-wheels, or other circular bodies each with one heat in the same apparatus or mill in accordance with my invention as and in the manner fully described in my aforesaid original application. The herein described invention is an essential feature in rolling or forming car wheels or other circular bodies in accordance with my invention described in my said original application and is original with applicant.

Another object of my invention is the provision of work-supporting means constructed so as to permit of interiorly cooling the same.

Another object of my invention is the provision of work-supporting means constructed so as to permit of exteriorly cooling the same.

My invention, among other objects herein described, has also for its object the provision of means capable of drawing away heat from the work-piece at its supported region during the rolling or operating process.

Another object is to provide piercers or work-supporting centers or work-supporting means which are adapted to engage or pierce or penetrate or center a heated work-piece at one or both sides and support the same while the work-piece is being rolled or operated on and to so construct said piercers or centers or supporting means and their axles that they may be interiorly cooled so as to cool the journals and bearings of said axles and so as to also draw away heat from the work-piece at its supporting region while the work-piece is being rolled or operated upon.

Another object is to provide a work-sup-

porting head or heads in which work-supporting axles are rotatably mounted and to exteriorly cool said work-supporting heads. Said exterior cooling of the parts of the 5 work-supporting head or heads prevents overheating of the journals and bearings of said axles and heads, and owing to the great area of the exterior faces of the work-supporting head or heads the cooling is done 10 in a more effective manner than is possible with internal cooling only. With the cooling system of this invention the machine is in condition to be operated continually at all times, which will be clear from an examination of the drawings.

This invention further contemplates a novel method or process of manufacturing car wheels or other circular bodies whereby such bodies or articles may be made in a 20 rapid, continuous, economical and commercial manner; at the same time assisting in securing a uniform density and homogeneity of the metal in the manufactured article which contributes materially to the strength 25 and durability of the same.

Other objects of my invention are, to provide a novel device for cooling the herein named piercers or work-supporting centers or work-supporting means and their axles 30 to prevent overheating of the journals and bearings of said axles during the rolling or operating process and for cooling the surface or surfaces of the center portion of the ingot, bloom, blank or other work-piece in 35 direct contact with said piercers or work-supporting centers to give to said supporting surfaces in contact with said piercers or work-supporting centers or work-supporting means a greater or harder supporting 40 resistance; a novel device for cooling the herein named work-supporting heads or supporting heads which support said axles with their piercers or work-supporting centers or work-supporting means and the 45 work-piece, and also for cooling the journals and bearings of the axles of said piercers or work-supporting centers or work-supporting means and of said work-supporting heads.

The above-mentioned objects of my invention 50 and others which appear in my aforesaid original application, places the apparatus or mill in condition to be operated continually at all times, thereby reducing the cost of operation in the manufacture of 55 car wheels and other circular objects. The production of car wheels and other circular objects is thereby greatly cheapened and the output increased.

Further objects of the invention will here- 60 inafter appear.

The invention consists in the novel method or process herein described and more particularly pointed out in the claims; and it also consists in the novel means, in the ar- 65 rangement of devices, in the novel features

of construction and in the arrangement and combination of parts herein described and more particularly pointed out in the claims.

In the accompanying drawings, in which I illustrate devices or means I prefer to employ in carrying out or practising my invention:

Figure 1 is a plan view and illustrates in a diagrammatic manner that portion of an apparatus or mill embodying my invention, 70 for rolling or forming car wheels or other circular bodies. The piercers or work-supporting centers or work-supporting means in this figure show a work-piece centrally or axially supported thereby and pressure applied equally to said work-supporting means at opposite sides of the work-piece. The work-piece in this figure is shown centrally pierced or centered by the piercers or work-supporting centers or work-supporting 75 means and supported thereby and is shown rolled with the one set of the rolls, as shown. Fig. 2 is a similar view showing greater pressure applied to said work-supporting means at one side of the work-piece than at 80 the other, thereby dishing the work-piece. The work-piece in this figure is shown completely rolled with all the rolls and dished to the form shown. Fig. 3 is a similar view illustrating said work-supporting means 85 and the rolls moved away from the work-piece and shows the work-piece or finished article ready to be removed from the apparatus or mill.

Fig. 4 is a sectional plan view of one of 100 my work-supporting heads showing my invention, the parts carried thereby, and the means for guiding said head for longitudinal movement. Fig. 5 is a cross-section of the work-supporting head and the hollow 105 work-supporting axle journaled therein, said section being taken on line 5—5, Fig. 6. Fig. 6 is a side elevation of the work-supporting head. Fig. 7 is a transverse section taken on line 7—7, Fig. 4, the work-supporting head being shown positioned within its guide which is also shown in transverse section. Figs. 8 and 9 show the adjusting parts 110 of said guide. Fig. 10 is an enlarged horizontal section through the water cooling or 115 other cooling medium arrangement for the work-supporting axle of my work-supporting head, the parts at the extreme right being, for the sake of illustration, turned in a different position than they will have when 120 in operation. Fig. 11 is an enlarged section of one of the herein named work-supporting centers or work-supporting means for forming dies attached to its axle as shown.

Fig. 12 is a side elevation of part of a pair of 125 my aligned work-supporting heads, and a work-piece between and supported by said work-supporting axles of said heads; in this figure is also shown the aligned guides for said supporting heads and the portion of the bed- 130

plate to which said guides are fixedly secured. The work-piece in this figure is shown centrally pierced or centered by said piercers or work-supporting means and supported thereby and ready to be operated upon; the dotted lines indicate the center or hub portion of the work-piece when formed in accordance with my invention as described in my said original application. 10 Fig. 13 is a cross-section taken through line 13-13, Fig. 12.

Figs. 14, 15 and 16 are diagrammatic views showing for instance a few of said piercers or work-supporting centers or work-supporting means and work-supporting heads in position during the rolling of ingots, blooms, blanks or other work-pieces into car wheels or other circular bodies. In Fig. 14 the work-piece is shown centrally pierced or centered by said piercers or work-supporting centers or work-supporting means and supported thereby and is also shown rolled with one set of the rolls as shown, it being similar to the illustration thereof shown on a small scale in Fig. 1. In Fig. 15 the work-piece is shown completely rolled with all the rolls and dished to the form shown, it being similar to the illustration thereof shown on a small scale in Fig. 2. 30 In Fig. 16 the work-piece shown in dotted lines is a worn car wheel which has been rolled to the form shown by the solid lines and, in this illustration, the piercers or work-supporting centers or work-supporting means or forming dies have the form, for instance shown in Fig. 11, which form is adapted either to reduce the outer diameter of the hub of the work-piece and the diameter of the bore of said hub, or to enlarge the 40 diameter of the bore of said hub.

Figs. 17, 18, 19 and 20 illustrate a few more of said piercers or work-supporting means and also part of said work-supporting axles to which they are secured and the work-supporting heads for said axles. Fig. 21 shows for instance, a blank (of which is shown the center portion only) in position ready to be pierced or centered with said piercers or work-supporting centers or work-supporting means shown in solid lines and it also shows, in dotted lines, said blank pierced or centered by said piercers or work-supporting means.

This invention, as hereinbefore said, is a 55 division of my aforesaid original application and, the parts of the apparatus or mill shown in the accompanying drawings are illustrative of parts of my said original application. It is, of course, understood that 60 I do not intend to limit myself to the use of the particular parts shown, as other means may hereafter be devised for carrying out my invention or method in a practicable manner.

65 Similar characters of reference indicate

corresponding parts throughout the several views, and also indicate the same corresponding parts in my said original application.

B¹ and B² are portions of the bed-plate. 70

E, E¹ are partly hollow spindles or axles provided with my cooling device; these axles are the herein named work-supporting axle, or axles, which also serve other purposes. 75

E¹, E², E³, E⁴, E⁵ and E⁶ show, for instance, different shapes of the herein named piercers or work-supporting centers, or work-supporting means, or forming dies and which may also be differently formed 80 than those herein shown and also to serve other purposes. There is practically no limit to the shapes or forms that said piercers or work-supporting centers or work-supporting means or forming dies may have. 85

F, F¹ and F² represent the work-piece from some of the many various forms or shapes it may have when put into the apparatus or mill to some of the many various forms or shapes which the finished article 90 or product may have (see my said original application).

G, G¹ are the roll shafts which have at one of their ends the herein named web finishing rolls. 95

G¹ and G² is, for instance, one set of the herein named finishing rolls. These rolls are laterally movable and are also axially adjustable or movable and are interchangeable and, there is practically no limit to the 100 forms or shapes that these rolls may have.

H is the herein-named tread or face finishing roll which acts against the peripheral face of the work-piece. This roll is movable toward and against and also away from the 105 peripheral face of the work-piece. There is practically no limit to the forms or shapes that this roll may have.

J, J¹ are the roll shafts, each of which has at one of its ends one of the herein named 110 edging and web rolling rolls.

J¹ and J² is, for instance, one set of said herein named edging and web rolling rolls. These rolls are laterally movable and are also axially movable and are interchangeable 115 and, there is practically no limit to the forms or shapes that these rolls may have.

K is the herein named tread or face rolling roll which acts against the peripheral face of the work-piece. This roll is movable toward and against and also away from the 120 peripheral face of the work-piece and it is also laterally movable. Like the other 125 rolls referred to, there is practically no limit to the forms or shapes that this roll may have.

Said piercers or work-supporting means are located one at each side of the blank or work-piece, and preferably revolve with the work-piece. For instance, during the pierc- 130

ing or penetrating or centering process, said piercers or work-supporting means are moved longitudinally toward or away from each other, or are moved as may be desired; 5 and during the dishing process they are also moved longitudinally with the center or hub portion of the work-piece, wheel or other article, as the case may be.

By the words "centering, or piercing or 10 penetrating and centering" used herein, I mean that, the ingot, bloom, blank or other work-piece is centered, or pierced or penetrated and centered in the apparatus or mill, by forcing either one or both said piercers 15 or work-supporting centers or work-supporting means against or into said work-piece by the pressure means O and N as shown in Fig. 1, and, as and in the manner fully described in my aforesaid original ap- 20 plication.

M, M are the herein named work-supporting heads; although so named they also serve other purposes, as will be observed from my aforesaid original application. 25 The axles E, E are carried and rotatably supported by said supporting heads M, M. Each of these axles E, E, has one of said herein named piercers or work-supporting centers or work-supporting means for in- 30 stance E¹ or E² or E³ or E⁴ or E⁵ or E⁶, &c., at one of its ends. These piercers or work- supporting centers or work-supporting means are interchangeable. Said heads M, M are longitudinally movable and are 35 moved, with their axles E, E and said piercers or work-supporting means for instance E¹, E⁴ or E², E² or E⁶, E⁶, &c., in line with the axis of the work-piece by means of the pressure cylinders O and N 40 (see Fig. 1) or by any other equivalent means. One of said heads M, M is operatively connected with the piston-rod O³ of the piston in cylinder O and is moved by the pressure in said cylinder O, and, the 45 other of said heads M, M is operatively connected with the piston-rod N³ of the piston in cylinder N and is moved by the pressure in said cylinder N.

With reference to Figs. 1, 2 and 3 illus- 50 trating the device for centering or for pierc- ing, or penetrating and centering ingots, blooms, blanks or other work-pieces, for supporting the same, for rolling, dishing or undishing, or for rolling and dishing or un- 55 dishing the same, and also for putting the work-pieces at their hub or center portions while so supported by said work-supporting means into clamped condition laterally or axially between said piercers or work-sup- 60 porting means and automatically keeping said hub or center portions in said clamped condition by constant pressure during the rolling and dishing or undishing process.

For piercing and centering, for instance, 65 a properly heated blank or work-piece F,

having the form shown in Figs. 12 or 21, the blank or work-piece F which, in these illustrations, has a thickness which is for instance the same or somewhat greater than the lateral thickness or width which the 70 marginal or rim portion of the car wheel or other article is to have when finished, is placed onto a raising, lowering and retaining device (see my aforesaid original ap- 75 plication) and lowered with said device to the position indicated in Fig. 21, wherein the outer portion or periphery (not shown in Fig. 21) of said blank F will be central, or approximately so, with said piercers or work-supporting means, which will then be 80 moved by the pressures in said cylinders N and O acting on the pistons of the piston- rods N³ and O³ which are operatively connected with said piercers or work-supporting means, as shown for instance in Fig. 1, 85 to the position shown for instance in the Fig. 21. The total pressure or force will then be delivered to the pistons of said pis- 90 ton-rods N³ and O³ to force, for instance, said piercers or centers E¹, E¹, &c., into said work-piece F, thus piercing or pen- 95etrating or centering the latter to the depth or depths as indicated, for instance, by the dotted lines for said centers E¹, E⁶ in the Fig. 21, or shown by solid lines, for instance, in Fig. 12; or, in case that the blank or work-piece has a thickness which is the same or somewhat greater than the length which 100 the hub of the car wheel or other article is to have when finished, then in such case the shoulders or flanges of said piercers or centers E⁶, E⁶ will come against the sides of the blank or work-piece as 105 for instance shown in the Figs. 1, 14 and 15. In Fig. 16 is shown, for instance, a previously finished or worn car wheel rerolled to the size and form of F², supported for instance by said piercers or centers or forming dies E², E², as shown. These centers or 110 forming dies are forced or placed over the outer diameter of the hub as shown and serve either to reduce or enlarge the diameter of the bore of the wheel or other article, as may be desired. In Fig. 11, I have shown in enlarged section, one of said piercers or centers or forming dies for instance E², E² having for instance the form 115 as shown, the piercing or center portion e²⁶ 120 which is either centrally enters the hole loosely or will be centrally forced into the hole or bore of the work-piece (as shown in Fig. 16), and the annular flange e²⁷ which is 125 separated from said piercing or center portion e²⁶ by an annular intervening space, is centrally forced over or placed over the outer peripheral part or diameter of the hub of the work-piece, by which process the central hole or bore of, for instance, either 130

previously formed or worn car wheels, may either be reduced or made larger so that the same may be reborod to the diameter of its original bore or to a larger diameter.

5 For instance; with reference to Figs. 1, 2 and 3, the rolling or forming process may begin with the herein named edging and web rolling rolls for instance J^1 , J^2 and tread or face rolling roll K and therewith 10 the blank or other work-piece may be rolled to either of the forms or shapes F^1 , for instance, such as shown in the Figs. 1 and 14 or similar forms. In case the finished article should be a dished car wheel having 15 the form or shape shown, for instance, in Figs. 3 or 15, the ingot, bloom, blank or other work-piece having been rolled by the herein named edging and web rolling rolls, for instance J^1 , J^2 and the tread or face roll- 20 ing roll K , to the form or shape F^1 in Fig. 1 or 14, and with said rolls in the position shown in said Fig. 1 or the rolls J^1 , J^2 may be moved somewhat toward the axis of the work-piece, the herein named web finishing 25 rolls for instance G^1 , G^2 and tread or face finishing roll H , may begin the finishing operation against the work-piece F^1 , and during said finishing operation the wheel may also be dished in the following manner:—

30 With the work-piece F^1 supported on said piercers or centers for instance E^6 , E^6 and with its hub or center portion automatically firmly clamped laterally between said piercers or centers and before the dishing commences, as shown in Fig. 1, the piston-rod N^2 of the cylinder N with one of the said work-supporting heads M , M and its said axle E and piercer or center E^6 now under constant and continuous pressure 40 from said cylinder N , causes the one piercer or center E^6 to press automatically and continuously toward and against the hub or center portion of this one side of said work-piece F^1 , and the piston-rod O^2 of the cylinder O with the other work-supporting head M and its axle E and piercer or center E^6 now also under constant and continuous pressure from the cylinder O , causes the other piercer or center E^6 to press automatically and continuously toward and against the hub or center portion of said work-piece F^1 at the other side thereof as shown in Fig. 1. Dishing of the work-piece 50 then takes place, while the work-piece is rotating and while the marginal or peripheral portion of the work-piece is laterally supported and retained by the rolls as shown, in the following manner: While either, any, or all the driven rolls or all the 55 rolls are in operation, the pressure in said cylinder N is gradually somewhat relieved or reduced, retaining therein however, the constant pressure required in said cylinder N to retain the aforesaid automatically 60 clamped condition of the hub or center por- tion of said work-piece laterally between said piercers or centers E^6 , E^6 , thereby causing the pressure or force in the cylinder O to overcome the resistance of the piston-rod N^2 and gradually moving the pistons and their rods O^2 , N^2 and O^2 , N^2 , with their said heads M , M and with the center or hub portion of the work-piece which as aforesaid is firmly held laterally or axially in said automatically clamped condition and revolubly 70 supported by the said piercers or centers E^6 , E^6 , while the work-piece is rotating, into the position shown in Fig. 2 in which position the work-piece or wheel is dished as shown. In this position, if necessary or de- 75 sired, the rolls may still be in operation for finishing and truing up the work-piece or wheel to the form or shape shown at F^2 in Fig. 2; or, instead of so reducing the constant pressure in said cylinder N , said dish- 80 ing can also be done, while the work-piece is rotating, by increasing the constant pressure in cylinder O so as to overcome the constant pressure in cylinder N . During 85 the dishing or rolling and dishing operation, the rim of the wheel or other article is laterally supported and retained by the rolls, as shown in Fig. 1 or 2. After the wheel or other article is completely rolled, dished and finished, the rolls and piercers 90 or centers may be pulled back, as shown in Fig. 3, thereby placing the finished wheel F^2 or other finished article onto the aforesaid raising, lowering and retaining device, which raises the finished wheel F^2 to a position above the work-supporting means or the rolls or above the apparatus or mill and from there said finished wheel F^2 is taken away by any suitable means and another 95 properly heated ingot, bloom, blank or other work-piece put in place of it and lowered and centered, or pierced or penetrated and centered, &c., as above described. In the positions shown in the Fig. 3, the piston-rods O^2 , O^2 and N^2 , N^2 and said piercers or centers E^6 , E^6 are pulled back and the finished wheel F^2 cleared to be removed as above 100 described.

105 Undishing and reddishing may be done in a similar manner as the dishing; in undishing, the dished object is placed on said piercers or centers and while so supported can be moved axially to suit the rolls and then undished while the object revolves.

110 Figs. 4 to 11 inclusive show in details one 115 of the said work-supporting heads M , M . Figs. 12 and 13 show the arrangement of said work-supporting heads M , M , the work-piece F in these figures being shown centrally pierced or centered by the piercers or centers E^6 , E^6 and ready to be operated upon; the dotted lines indicating the center or hub portion of the work-piece when formed in accordance with my invention as described in my said original application. 120

125 130

The said head M is named the work-supporting head although it serves other purposes as will be observed from my said original application. Fig. 4 is a plan view with 5 the cooling water or other cooling medium inlet for said work-supporting head M shown in section through 4—4, Fig. 6. Fig. 5 is a section through 5—5, Fig. 6. Fig. 6 is a side elevation with the plates M¹⁰ and M²⁵ 10 of one side of the water or other cooling medium boxes removed. Fig. 7 is a sectional end view of Fig. 6 with lower part in section through 7—7, Fig. 4, also showing part of the guide bearing M³¹ firmly 15 supporting said work-supporting head M. Fig. 8 is a section through 8—8, Fig. 4, showing the guide pressure plate M³² and wedge adjusting arrangement with adjusting set screws M³⁸. Fig. 9 is a section 20 through 9—9, Fig. 4, showing the guide pressure plate M³² and wedge adjusting arrangement with the wedge pull back screws M⁴⁰. Fig. 10 is an enlarged section through 25 the water or other cooling medium arrangement for the axle E with its piercer or work-supporting center, also showing the parts connected therewith. The work-supporting head M is provided as shown with an end-plate M¹ which is firmly bolted to 30 the head M by the screws and nuts M² as shown. The said parts M and M¹ also form the supports for the bearings M³, M⁴ and M⁵ for the herein named work-supporting axle E. Said end plate M¹ also supports 35 with its inner end as shown, the ball pressure plate M⁶. Between the supporting head M and end plate M¹ the supporting axle E is partly enlarged in diameter over which enlargement is fitted the other ball 40 pressure plate M⁷. Between these two pressure plates M⁶ and M⁷ are placed the balls M⁸ sufficiently large in diameter and sufficient in number to safely resist the pressure during the centering or piercing and 45 centering process of the ingots, blooms, blanks or other work-pieces and during the lateral clamping process of said work-pieces at their hub or center portions between said piercers or centers or supporting means, and 50 during the dishing process of the wheel or other article. These axles E, E, have at one end the said piercers or centers or supporting means, as for instance E¹, E¹ or E², E² or E³, E³ or E⁴, E⁴ or E⁵, E⁵ or E⁶, E⁶, &c., as for instance herein shown. These 55 piercers or centers or supporting means are removably fastened to one end of said axles E, E by the shoulder e² and the pins e¹, e¹, as shown, or by any other suitable means. 60 From the other end, each of said axles E, E is provided with a central bore e³, as shown, which bore is enlarged at its open end and into which is fitted a sleeve or pipe piece e⁴ forming also a journal with said bore. Said 65 sleeve e⁴ has its outer diameter near its one end enlarged, as shown at e⁵, and said axle E at its open end has formed a thread e⁶ over which is fitted a nut e⁷ forming with the end of said axle E and with the gland e⁸ a regular stuffing box. The pin e⁹ revolves 70 said gland e⁸ with the said axle while said sleeve e⁴ is held against revolving. Said sleeve e⁴ has fitted thereto at its outer end a T-shaped end connecting piece e¹⁰ provided with the threaded end connecting parts e¹², 75 e¹⁶ and e¹⁷. A pipe e¹¹ is screwed into the inner end of the connecting part e¹² and reaches to a point a short distance of the end of said bore e³. An elbow e¹³ is screwed into the outer end of e¹² and connects with 80 pipe e¹¹, as shown. The end of said sleeve e⁴ is screwed into the end e¹⁷ of the connecting piece e¹⁰ and said sleeve e⁴ surrounds said pipe e¹¹ and leaves a certain open space 85 between said sleeve or pipe piece e⁴ and pipe e¹¹. The parts e¹⁰ and e¹³, as shown in Fig. 10, are for the sake of illustration turned in a different position than they will have when in operation. When in operation they may have the position shown in 90 the Figs. 4, 6 and 7. The cooling water or other cooling medium enters at the elbow e¹³ at the point indicated by the arrow e¹⁴, passes through said elbow e¹³ and through the pipe e¹¹ and then flows in the direction 95 indicated by the arrows e¹⁵ around the outside of said pipe e¹¹ into said T-shaped connection piece e¹⁰ and from there through the short pipe e¹⁸ screwed into the end e¹⁶ and into and out through port e¹⁹ and channel e²⁰ and from there through channels 100 formed by parts of the bed-plate B², B², and from there is taken away by any suitable means, such as pipes or channels, &c. The axle E with its said piercer or center revolves with the work-piece, but said sleeve e⁴ and pipe e¹¹ with their T-shaped end connecting piece e¹⁰ are held against revolving. To this end said connecting piece e¹⁰ is 105 fastened by the bolts e²², e²², as shown, to the cross-piece e²³, which latter is held by the thread and nuts e²⁴, e²⁴ to the extensions e²⁵, e²⁵ of two of the said studs M², as shown. By the means shown, said work-supporting axles E, E with their piercers or 110 work-supporting centers or work-supporting means for instance E¹, E¹ or E², E², &c. their journals M³, M⁴ and M⁵ and the ball thrust bearing formed by the said parts M⁶, M⁷ and M⁸ are practically kept cool and also 115 take part of the heat away from the center or supporting portion of a heated work-piece to give to the supporting surface or the portion of the work-piece in contact with the supporting centers a greater or harder supporting resistance. The inlet flow of the water or other cooling medium can easily be regulated by a valve for the inlet e¹¹ which may be placed near the elbow e¹³. The cooling water or other cool- 120 125 130

ing medium for the outer sides of the said work-supporting head M enters, as indicated by the arrow M⁹, into and through the elbow M¹⁰ and nipple M¹³, passing thence into 5 a water or cooling medium chamber or reservoir or box M¹¹ which is formed into the upper part of said head M with the sides M¹², and M¹⁴ over which are fastened by means of screws M¹⁵ the plates M¹⁶, M¹⁶ 10 which close the two sides of said water or other cooling medium box M¹¹. At the lower end of said box these plates M¹⁶, M¹⁶ leave openings M¹⁷, M¹⁷ which extend the total inside width of said water or other 15 cooling medium box and through which the cooling water or other cooling medium flows down in contact with the sides, as indicated by the arrows M¹⁸, and enters the lower boxes or channels M¹⁹, M¹⁹ formed by 20 and connected with said head M by the parts M²⁰, M²¹, M²² and M²³ and over which are fastened by means of the screws M²⁴ the plates M²⁵, M²⁵ as shown. From these lower boxes M¹⁹, M¹⁹ the water or other cooling 25 medium flows, as indicated by the arrows, into and out through said port e¹⁹ and channel e²⁰ and through the before-mentioned channels formed by parts of the bed-plate B², B², and from said last-mentioned channels conducted 30 away by any suitable means such as pipes, channels, &c. By these means shown, each of said work-supporting heads M, M with its bearings and axle may practically be kept cool and thus also assist in taking part 35 of the aforesaid head away from the supporting surface of the work-piece to give said supporting surface in contact with said piercers or work-supporting centers or work-supporting means a greater or harder supporting resistance. The inlet flow of water 40 or other cooling medium can easily be regulated by a valve for the inlet M⁹ which may be placed near the elbow M¹⁰.

Each of said work-supporting heads M, 45 M is also formed at its lower side with a guide or slide block forming bearings at M²⁶, M²⁷, M²⁸, M²⁹ and M³⁰; the sides M²⁶, M²⁷ and M²⁸ forming the bearings with the guide piece M³¹; the sides M²⁹ and M³⁰ 50 forming the bearings with the guide pressure plate M³². The bolts M³⁴ reach through the slotted holes M⁴³ in said pressure plate M³² and press the said guide pressure plate M³² against the supporting sides M²⁸ and 55 M³⁰ of the guide piece M³¹, and when the said bolts M³⁴ are screwed up, said pressure plate M³² is rigidly held therewith and practically forms one piece with said guide piece M³¹. A wedge piece M³⁵ is placed between said pressure plate M³² and said guide piece M³¹, as shown, and with its vertical side M³⁶ forms bearing with said plate M³² and with its inclined side M³⁷ forms bearing with said guide piece M³¹. Set screws 60 M³⁸ having lock nuts M³⁹, as shown, fit into

tapped holes of said pressure plate M³² and bear against said wedge piece M³⁵ as shown. Pull back screws M⁴⁰ with sufficiently long threads M⁴¹ reach through the slotted holes M⁴² in said pressure plate M³², as shown, and are fitted into tapped holes in said wedge piece M³⁵ as shown. To adjust said guide bearing, the nuts on said bolts M³⁴ are sufficiently loosened and the screws M⁴⁰ backed up and then the wedge piece M³⁵ forced or moved downward by means of said screws M³⁸. The nuts on said bolts M³⁴ are then screwed up or set up tight, and the screws M⁴⁰ again screwed down to prevent the wedge piece M³⁵ from working 70 downward. These screws M⁴⁰ are also placed there for the purpose of pulling the wedge upward in case it has been forced down too much during the adjustment by the set screws M³⁸. 75

The said work-supporting heads M, M provided with the axles E, E and their said piercers or work-supporting centers or work-supporting means, for instance E⁶, E⁶ are located one at each side of the work-piece as for instance shown in Figs. 1, 2, 3 and 12, and during the rolling process may be fixed; but said piercers or work-supporting centers or work-supporting means with their axles will revolve with the ingot, bloom, blank or other work-piece in the said bearings of said work-supporting heads M, M, and, during the piercing or centering, dishing or undishing, rolling and dishing or undishing processes, said work-supporting 90 heads M, M with their axles E, E, and said piercers or work-supporting centers or work-supporting means, for instance E⁶, E⁶, are moved longitudinally in line with the axis of the work-piece, by means of the 95 pressures in the cylinders O and N (see Fig. 1) or by any other equivalent means, and are so moved toward or away from each other and may also be moved together in either direction, or one of them may be retained in any position while the other is moved toward or away from the one so retained during the piercing or centering process and are also longitudinally moved when removing said piercers or centers 100 from the work-piece or finished object. During the rolling and dishing or during the undishing, dishing, undishing and redishing processes said centers are moved with the center or hub part of the work-piece, as the case may require and as and in the manner fully described in my aforesaid original application. At one side of the work-piece one of said work-supporting heads M, M is so moved by the pressure in 105 the cylinder O, and at the other side of the work-piece the other work-supporting head M is so moved by the pressure in the other cylinder N as shown. 110

Each of the said work-supporting heads 115

120

125

130

M, M is also formed with a socket part M⁴⁴ which receives one end of the piston-rod of its coöperating pressure cylinder. To the part M⁴⁴ of said work-supporting head M, shown in detail in Figs. 4 to 10 inclusive, is attached the piston-rod O³ of the cylinder O by means of the shoulder O⁴ and the key O⁵, as shown in the Fig. 6. To the part M⁴⁴ of the other work-supporting head M at the other side of the work-piece is attached the piston-rod N³ of the other cylinder N by similar means, as shown in said Fig. 6.

With reference to the Figs. 1, 2, 3 and 4 to 13 inclusive, O is the said pressure cylinder for the work-supporting head M with its axle and said piercer or work-supporting center or work-supporting means located at one side of the work-piece; and, N is the said pressure cylinder for the other work-supporting head M with its said axle and said piercer or work-supporting center or work-supporting means, located at the other side of the said work-piece. Cylinder O has a piston with a piston-rod O³ and a piston-rod O², passing through the cylinder heads at both ends of the cylinder O (see Fig. 1). The piston-rod O³ is provided at its outer end with the said shoulder O⁴ and key O⁵ and is firmly held thereby and connected with said work-supporting head M, as shown in Figs. 6 and 7. The details and description of the pressure cylinder N and its connecting parts for said other work-supporting head M at the other side of the work-piece, are similar to those described above and fully described in my aforesaid original application. The said piercers or work-supporting centers or work-supporting means, for instance E⁶, E⁶, with their work-supporting heads M, M are moved longitudinally and operated by the means of said cylinders N and O with their piston- rods N², N³ and O², O³ as and in the manner described in my aforesaid original application.

Where in the specification and claims the words "ingot, bloom or blank" are used, it is intended to mean the work-piece to be operated upon, and the word "work-piece" is used herein in a broad sense and is intended to include an ingot, bloom, blank, car wheel, or any other unfinished or completely finished circular, or approximately circular or other shaped object adapted to be rolled, re- rolled, reworked or reformed or otherwise operated upon, either to entirely change its shape, or only partly change its shape or outline, or to change its dimensions in whole, or part as desired. In other words "work-piece" means any object to be operated upon.

The herein shown and described method of and means for supporting the work-piece and for cooling the said piercers or work-supporting means, the work-supporting

axles and the work-supporting heads enables the work-piece to be centrally pierced or penetrated and rotatably supported in a rapid manner without becoming loose on its supporting means and by reason of which a rapid, continuous and economical operation of the work-pieces will result therefrom; and at the same time a uniform density and homogeneity of the metal in the finished article, rolled or formed in accordance with my invention, is secured and the finished article will also be rolled or formed perfectly true and to balance.

While I have shown and described the device or means which I now consider best and most practicable for carrying out my method of supporting a work-piece and for cooling the supporting means during the rolling or operating process, also the means for carrying out my method of drawing away heat from the work-piece at its supported region during the rolling or operating process to give to said supporting surfaces of the work-piece a greater and harder supporting resistance, it is, of course, understood that I do not wish to be confined to the exact construction herein shown and described, and that my method may be carried out in various other ways; also that apparatus or means other than herein shown and described may be provided without departing from the spirit of my invention or sacrificing any of the advantages thereof.

The features of my invention herein described are not all claimed herein, but such features not herein claimed are covered by claims within my aforesaid original application and within applications filed by me and having the hereinbefore mentioned serial numbers and filing dates.

I claim as my invention:

1. The herein described method of cooling the work-supporting means in an apparatus or mill for rolling or forming car wheels or other circular bodies, which consists in interiorly and in exteriorly cooling said supporting means.

2. The herein described method of cooling the work-supporting means in an apparatus or mill for rolling or forming car wheels or other circular bodies, which consists in causing a cooling medium to circulate through the interior of the central rotating portion of said work-supporting means.

3. The method of cooling the means for supporting a heated work-piece during the rolling or operating process in an apparatus or mill for rolling or forming car wheels or other circular bodies, which consists in applying a cooling medium to the end portion or portions of the work-supporting means adjacent the work-piece without having said cooling medium come in direct contact with the work-piece.

4. The method of cooling the rotating

part or parts of the means supporting a heated work-piece during the rolling or operating process, which consists in interiorly cooling the rotating part or parts of the work-supporting means adjacent the work-piece.

5. The method of cooling the hollow axles or supporting means which centrally support a heated work-piece during the rolling or operating process in an apparatus or mill for rolling or forming car wheels or other circular bodies, which consists in introducing a circulating cooling medium into said hollow axles or supporting means to retain 15 the ends thereof applied to the work-piece in a cooled condition.

6. The herein described method of cooling the work-supporting means in an apparatus or mill for rolling or forming car wheels or other circular bodies, which consists in causing a cooling medium to flow over and in contact with the exterior surfaces or exterior portions of said supporting means.

7. The herein described method of cooling the work-supporting means in an apparatus or mill for rolling or forming car wheels or other circular bodies, which consists in causing a cooling medium to circulate through the interior of the central 25 and rotating portion of said supporting means, and in causing a cooling medium to flow over and in contact with exterior surfaces or exterior portions of said supporting means.

35. 8. The method of cooling the work-supporting devices having means engaging the central portion of a heated work-piece and supporting the same during the rolling or operating process in an apparatus or mill for 40 rolling or forming car wheels or other circular bodies, which consists in interiorly cooling the engaging means of said devices, and in exteriorly cooling said devices.

9. The method of cooling the work-supporting devices having means engaging a heated work-piece during the rolling or operating process in an apparatus or mill for rolling or forming car wheels or other circular bodies, which consists in causing a cooling 50 medium to circulate through the interior of the engaging means of said devices adjacent the work-piece, and in causing a cooling medium to flow over and in contact with exterior surfaces or exterior portions 55 of said devices.

10. The herein described method of cooling the work-supporting means in an apparatus or mill for rolling or forming car wheels or other circular bodies, which consists in causing a cooling medium to circulate through the interior of the central portion of said supporting means, and in causing a cooling medium to flow in contact with the exterior portion or portions of said supporting means.

11. The method of partly cooling or taking away part of the heat from the center or supported portion of a heated work-piece while the same is centrally supported in an apparatus or mill for rolling or forming car 70 wheels or other circular bodies, which consists in cooling the center or supporting portion of the work-piece through the medium cooling the parts supporting the work-piece.

12. The method of cooling the rotating axle or axles or the rotating part or parts of the device or devices for supporting a heated work-piece during the rolling or operating process in a mill for rolling or forming 80 car wheels or other circular bodies, which consists in directing or feeding a cooling medium interiorly to the inner end or ends of said axle or axles adjacent the work-piece and from there cause said cooling medium 85 to flow back through the interior and out of said axle or axles.

13. The method of cooling the work-supporting device or devices having a hollow axle or axles provided with means at the 90 end or ends to engage a heated work-piece during the rolling or operating process, which consists in directing or feeding a cooling medium interiorly to the inner end or ends of said axle or axles adjacent said 95 end means or adjacent the work-piece and from there cause said cooling medium to flow back through the interior and out of said axle or axles, and in causing a cooling medium to flow over and in contact with the exterior surfaces or exterior portions of 100 said work-supporting device or devices.

14. The method of cooling the work-supporting devices having means to engage a heated work-piece during the rolling or operating process, which consists in interiorly 105 cooling the work-engaging ends of the engaging means of said devices.

15. The method of cooling the work-supporting device or devices having end-means 110 to engage a heated work-piece during the rolling or operating process, which consists in interiorly cooling the work-engaging ends of the engaging means of said devices, and in causing a cooling medium to flow over 115 and in contact with exterior surfaces or exterior portions of said device or devices.

16. The method of partly cooling or taking away part of the heat from the center or supporting portion of a heated work-piece while the same is centrally engaged by supporting means during the operation of rolling or forming said work-piece into a car wheel or other circular body, which consists in applying a cooling medium to the 120 work-engaging ends of said supporting means without having said cooling medium come in direct contact with the work-piece.

17. The method of conducting part of the heat away from the central or supporting 130

portion of a heated work-piece while the same is centrally supported and is being rolled or operated on, which consists in interiorly cooling the end portions of the supporting means centrally supporting the work-piece.

18. The method of centering or piercing or penetrating a heated work-piece, which consists in moving or forcing a pair of 10 alined piercing or work-supporting axles having piercers or work-supporting means at adjacent ends against the work-piece, in applying piercing or centering pressure against said axles to cause said piercers or 15 work-supporting means to pierce or penetrate or center the work-piece and to cause the metal thereof replaced by said piercers or work-supporting centers to flow into another part of the work-piece, and in cooling 20 said piercing or work-supporting axles from the interior.

19. The method of centering or sizing the outer or peripheral hub portion of a heated work-piece having a central hub whereon 25 said work-piece is adapted to be supported and for cooling or taking part of the heat away from the hub or supporting portion of the work-piece during the rolling or operating process while the same is so supported, 30 which consists in moving or forcing a pair of alined and oppositely-arranged forming or work-supporting devices over said hub portion, and in cooling said forming or work-supporting devices.

35 20. The method of centering or sizing the outer or peripheral hub portion of a heated work-piece having a central hub, and rotatably supporting said work-piece on its said outer or peripheral hub portion while 40 the work-piece is being rolled or operated upon, and for cooling or taking part of the heat away from the hub or supporting portion of the work-piece while the work-piece is supported and is being rolled or operated 45 upon, which consists in moving or forcing a pair of alined and oppositely arranged forming or work-supporting devices over said hub portion and supporting the work-piece during the rolling or operating process, and in cooling said devices and thereby 50 drawing heat away from said hub or supporting portion of the work-piece while the work-piece is so supported, thereby providing, during the rolling or operating process, 55 a greater or harder supporting resistance at the supporting portions of the work-piece engaged by said forming or work-supporting devices.

60 21. The method of rolling or forming car wheels or other circular bodies from heated ingots, blooms, blanks or other work-pieces, which consists in applying axles or work-supporting means centrally to the work-piece to support the same, in cooling 65 said axles or supporting means, and in ap-

plying rolling means against the supported work-piece to roll or form the same to the form of a car wheel or other circular body.

22. The method of rolling or forming circular articles from heated ingots, blooms, 70 blanks or other work-pieces, which consists in applying the end or ends of a hollow or partly hollow axle or axles or supporting means centrally to the work-piece to support the same, and in introducing a cooling 75 medium into said hollow or partly hollow axle or axles or supporting means to retain the ends thereof applied to the work-piece in a cool condition, and in applying rolling means against the so supported work-piece 80 to roll or form the same to desired form or shape.

23. The method of rolling or forming circular articles from heated ingots, blooms, 85 blanks or other work-pieces, which consists 85 in applying axles or supporting means centrally to the work-piece to support the same, in cooling said axles or supporting means at the end portions adjacent the work-piece, and in applying rolling means against the 90 work-piece to roll or form the same into desired form or shape.

24. The method of rolling or forming circular objects from heated ingots, blooms, 95 blanks or other work-pieces, which consists 95 in centrally and rotatably supporting the work-piece, in partly cooling the center or supporting portion of the work-piece, in applying rolls against the work-piece to roll or form the same into desired form or shape. 100

25. The method of rolling or forming circular objects from heated ingots, blooms, 100 blanks or other work-pieces, which consists 100 in placing the work-piece between two alined work-supporting devices having centers or piercers or work-supporting means, in therewith engaging the central portion of the work-piece, in interiorly cooling the centers or piercers or work-supporting 105 means of said devices, in exteriorly cooling said devices, and in applying rolls against the work-piece to roll or form the same into desired form or shape.

26. The method of rolling or forming circular objects from heated ingots, blooms, 115 blanks or other work-pieces and of cooling or taking away part of the heat from the center or supporting portion of the work-piece while the same is centrally supported and is being rolled or operated on, which consists 120 in placing the work-piece between two alined work-supporting devices having centers or piercers or work-supporting means at adjacent ends adapted to engage the central portion of the work-piece, in interiorly cooling the centers of said devices, in exteriorly cooling said devices, and in applying rolls against the work-piece to roll or form the same into desired form or shape. 125

27. The method of rolling or forming a 130

heated object into desired circular form, which consists in supporting the object centrally on rotatable axles or supporting means, in cooling said axles or supporting means, and in applying rolls to exposed surfaces of the object to roll the same where desired to desired form or shape.

28. The method of rolling or forming a heated object into a car wheel, disk-wheel or other circular form or shape, which consists in centrally supporting the object, in partly cooling the center or supporting portion of said object, in applying rolls against said object to roll or form the same into a car wheel, disk-wheel or other circular form or shape.

29. The method of cooling or taking away part of the heat from the center or supporting portion of a heated work-piece while the same is centrally supported and is being rolled or formed into a car wheel or other circular body, which consists in placing the work-piece between two work-supporting devices having centers engaging the central portion of the work-piece, in interiorly cooling the centers of said devices and in exteriorly cooling said devices.

30. In an apparatus or mill for rolling or forming car wheels or other circular bodies, means for centrally and rotatably supporting a work-piece in a position immovable in the direction of a line at right angles with the axis of the work-piece, and means for cooling said supporting means.

31. In an apparatus or mill for rolling or forming car wheels or other circular bodies, a pair of alined and axially movable work-supporting heads arranged at opposite sides of a work-piece, alined work-supporting axles in said heads adapted to support a work-piece therebetween, and means for cooling said axles.

32. In an apparatus or mill for rolling or forming car wheels or other circular bodies, means for centrally and rotatably supporting a work-piece, and means for internally cooling the ends of said supporting means adjacent the work-piece.

33. In an apparatus or mill for rolling or forming car wheels or other circular bodies, a pair of rotatably journaled and alined hollow work-supporting axles adapted to support a work-piece therebetween, and means for interiorly cooling said rotating axles.

34. In an apparatus or mill for rolling or forming car wheels or other circular bodies, a pair of alined work-supporting heads arranged at opposite sides of a work-piece, a work-supporting axle rotatably mounted in each of said heads having its axis coincident with the axis of the work-piece, said work-supporting axles being adapted to support the work-piece therbetween, and means for cooling said axles.

35. In an apparatus or mill for rolling or forming car wheels or other circular bodies, a supporting head arranged at one side of a work-piece and provided with a dishing or work-supporting axle in line with the axis 70 of the work-piece and rotatably supported in said supporting head, said axle being adapted to support the work-piece, and means for cooling said axles.

36. In an apparatus or mill for rolling or forming car wheels or other circular bodies, a supporting head longitudinally movable, a power or pressure device connected with said head for moving the same, a dishing or work-supporting axle in line 80 with the axis of the work-piece and rotatably mounted in said head, said axle being adapted to support a work-piece thercon, and means for cooling said axle.

37. In an apparatus or mill for rolling or forming car wheels or other circular bodies, the combination with a support having alined guide pieces thereon, of a supporting head longitudinally movable in each of said guide pieces, a power or pressure device operatively connected with each of said heads for moving the same longitudinally, alined piercing or work-supporting axles rotatably mounted in said heads and adapted to support a work-piece therebetween, and means 95 for cooling said axles.

38. In an apparatus or mill for rolling or forming car wheels or other circular bodies, a pair of alined supporting heads arranged at opposite side of a work-piece, alined hollow or partly hollow piercing or work-supporting axles rotatably supported in said heads and adapted to support the work-piece therebetween, and means for internally cooling said axles.

39. In an apparatus or mill for rolling or forming car wheels or other circular bodies, a pair of alined hollow or partly hollow piercing or work-supporting axles arranged to support a work-piece therebetween, and means for internally cooling said axles.

40. In an apparatus or mill for rolling or forming car wheels or other circular bodies, a hollow or partly hollow dishing or work-supporting axle arranged to centrally support a work-piece thereon, and means for internally cooling said axle.

41. In an apparatus or mill for rolling or forming car wheels or other circular bodies, a pair of alined supporting heads arranged 120 at opposite sides of a work-piece and longitudinally movable, power or pressure devices operatively connected with said heads to move the same longitudinally, alined hollow or partly hollow work-supporting axles 125 rotatably mounted in said heads, and means for internally cooling said axles.

42. In an apparatus or mill for rolling or forming car wheels or other circular bodies, a pair of alined work-supporting elements,

means for moving said elements toward and from each other to engage a work-piece positioned therebetween or to release the same, and means for cooling said work-supporting elements.

43. In an apparatus or mill for rolling or forming car wheels or other circular bodies, a pair of alined hollow work-supporting elements, means for moving said elements toward and from each other to engage a work-piece positioned therebetween or to release the same, and means for internally cooling said work-supporting elements.

44. In an apparatus or mill for rolling or forming car wheels or other circular bodies, the combination with a support having alined guide pieces, of a work-supporting head longitudinally movable in each of said guide-pieces, power or pressure devices connected with said heads for moving the same longitudinally, alined hollow piercing or dishing or work-supporting axles rotatably mounted in said heads, and means for internally cooling said axles, said axles having piercers or work-supporting means at adjacent ends to engage and support a work-piece therebetween.

45. In an apparatus or mill for rolling or forming car wheels or other circular bodies, a pair of alined and axially movable work-supporting heads arranged to support a work-piece therebetween, and means for externally cooling said work-supporting heads.

46. In an apparatus or mill for rolling or forming car wheels or other circular bodies, a dishing or work-supporting head arranged at one side of a work-piece to support the same, and means for externally cooling said dishing or work-supporting head.

47. In an apparatus or mill for rolling or forming car wheels or other circular bodies, a supporting head arranged at one side of a work-piece, a dishing or work-supporting axle in line with the axis of the work-piece, said axle being rotatably mounted in said work-supporting head and adapted to support the work-piece, and means for externally cooling said work-supporting head.

48. In an apparatus or mill for rolling or forming car wheels or other circular bodies, a pair of alined work-supporting heads arranged at opposite sides of a work-piece and longitudinally movable, power or pressure devices connected with said heads for moving the same, piercing or work-supporting axles rotatably mounted in said heads and adapted to support a work-piece therebetween, and means for externally cooling said work-supporting heads.

49. In an apparatus or mill for rolling or forming car wheels or other circular bodies, the combination with a support having alined guide pieces, of a work-supporting head longitudinally movable in each of said

guide pieces, means for moving said heads longitudinally, piercing or work-supporting axles mounted in said heads and adapted to support a work-piece therebetween, and means for externally cooling said work-supporting head.

50. In an apparatus or mill for rolling or forming car wheels or other circular bodies, a hollow or partly hollow dishing or work-supporting axle arranged to support a work-piece, and a feed pipe for a cooling medium arranged centrally within said axle and separated from the wall thereof by an intervening space, and an outlet for the escape of the cooling medium.

51. In an apparatus or mill for rolling or forming car wheels or other circular bodies, a pair of hollow or partly hollow piercing or work-supporting axles arranged to support a work-piece therebetween, and a feed pipe for a cooling medium arranged centrally within each of said axles and separated from the wall thereof by an intervening space, each of said intervening spaces having an outlet for the escape of the cooling medium.

52. In an apparatus or mill for rolling or forming car wheels or other circular bodies, a pair of alined hollow axles arranged to support a work-piece therebetween, each axle having one end open and its other end closed, and a feed pipe for a cooling medium extending into each axle from its open end to a point near its closed end and having its inner end open, said feed pipes being arranged centrally within said axles and separated from the walls of the latter by annular intervening spaces, and an outlet at the open end of each of said axles for the escape of the cooling medium from the axle.

53. In an apparatus or mill for rolling or forming car wheels or other circular bodies, the combination with a support, of a pair of work-supporting heads arranged in alinement and longitudinally movable on said support, power or pressure mechanism for moving said heads longitudinally, hollow piercing or work-supporting axles arranged in alinement and having piercing or forming or work-supporting means at adjacent ends, said axles being rotatably mounted in said heads and with their piercing or forming or work-supporting means being adapted to form, or pierce, or penetrate, and support a work-piece situated therebetween, and a feed pipe for a cooling medium arranged centrally within each of said axles and separated from the wall thereof by an intervening space, each of said intervening spaces having an outlet for the escape of the cooling medium.

54. In an apparatus or mill for rolling or forming car wheels or other circular bodies, the combination with a support, of a pair of

70

75

80

- work-supporting heads arranged in alignment and longitudinally movable on said support, each of said heads having a bearing or bearings and being chambered at one end 5 to provide a shoulder, a plate removably held to said chambered end, alined piercing or work-supporting axles rotatable in the bearings of said heads and having piercers or work-supporting means at adjacent ends, 10 said axles being hollow from one end and having enlargements between their ends bearing against said shoulders, anti-friction thrust bearings between said enlargements and said end plates, a sleeve fitted into each 15 of said axles at their hollow ends, a stuffing box applied to each axle at the hollow end through which said sleeve extends, and feed pipes for a cooling medium passing through said sleeves and entering said axles, said 20 feed pipes being separated from the walls of said sleeves and axles by intervening spaces through which the cooling medium passes after escaping from said feed pipes.
55. In an apparatus or mill for rolling or forming car wheels or other circular bodies, the combination of a pair of work-supporting heads arranged in alinement, each head having a longitudinal bore enlarged at one end to provide a chamber, 25 piercing or work-supporting axles rotatable in the bores of said heads and adapted for action against a work-piece situated between the adjacent ends thereof, said axles having enlargements between their ends bearing 30 against one of the walls of said chambers, thrust bearings between said enlargements and the opposite walls of said chambers, and feed pipes for a cooling medium arranged centrally within said axles and separated 35 from the walls thereof by intervening spaces for the passage of the cooling medium therethrough.
56. In an apparatus or mill for rolling or forming car wheels or other circular bodies, 40 the combination of alined work-supporting heads arranged for longitudinal movement, each head having a longitudinal bore therein, piercing or work-supporting axles rotatable in the bores of said heads and 45 adapted to have a work-piece situated therebetween, stuffing boxes applied to the distant ends of said axles, a sleeve fitting into each of said axles and extending through the stuffing box thereof, and feed pipes for a 50 cooling medium passing through said sleeves and entering said axles, said feed pipes being separated from the walls of said sleeves and axles by intervening spaces for the passage of the cooling medium therethrough.
57. In an apparatus or mill for rolling or forming car wheels or other circular bodies, 55 a piercing or dishing or work-supporting head arranged in alinement or approximately in alinement with the axis of a

work-piece, and means for feeding a cooling 65 medium to said head and causing the same to flow in contact with the sides of said head.

58. In an apparatus or mill for rolling or forming car wheels or other circular bodies, a pair of alined work-supporting heads arranged at opposite sides of a work-piece, and means for feeding a cooling medium to 70 said heads and causing the same to flow in contact with the sides of said heads.

59. In an apparatus or mill for rolling or forming car wheels or other circular bodies, a pair of alined work-supporting heads arranged at opposite sides of a work-piece and longitudinally movable, each of said heads being provided at its upper end with a 75 reservoir or chamber for a cooling medium having outlets to cause the cooling medium to flow in contact with the sides of said heads.

60. In an apparatus or mill for rolling or forming car wheels or other circular bodies, the combination with a support, of a pair of work-supporting heads arranged in alinement and longitudinally movable on said support, each of said heads being provided 85 at its upper end with a reservoir or chamber for a cooling medium, said reservoirs or chambers having outlets to cause the cooling medium to flow in contact with the sides of said heads, and troughs at opposite sides of 90 each head at points beneath said outlets to receive the cooling medium after passing in contact with the sides of the head.

61. In an apparatus or mill for rolling or forming car wheels or other circular bodies, 100 a piercing or dishing or work-supporting head alined or approximately alined with the axis of a work-piece, a hollow piercing or dishing or work-supporting axle in said head adapted to support a work-piece, means 105 for feeding a cooling medium to said head and causing the same to flow in contact with the sides of the head to cool the same, and means for cooling said axle from the interior.

62. In an apparatus or mill for rolling or forming car wheels or other circular bodies, a supported work-supporting head, a work-supporting axle rotatable in said head and adapted to support a work-piece, means for 110 cooling said work-supporting head, and means for cooling said work-supporting axle.

63. In an apparatus or mill for rolling or forming car wheels or other circular bodies, 115 a supported work-supporting head, a hollow axle in said head, means for feeding a cooling medium to said work-supporting head to cool the same, and means for internally cooling said axle.

64. In an apparatus or mill for rolling or forming car wheels or other circular bodies, a work-supporting head, a hollow axle ro-

- tatable in said head and arranged in alignment with the axis of a work-piece, means for externally cooling said work-supporting head, and means for internally cooling said 5 axle.
65. In an apparatus or mill for rolling or forming car wheels or other circular bodies, a pair of work-supporting heads arranged in alignment, an axle in each of said heads, 10 said axles being adapted to engage opposite sides of a work-piece with their adjacent end-means, means for feeding a cooling medium to said work-supporting heads and causing the same to flow in contact with the 15 sides of the same, and means for internally cooling said axles.
66. In an apparatus or mill for rolling or forming car wheels or other circular bodies, a pair of aligned work-supporting heads, a 20 piercing or work-supporting axle in each of said heads, said axles having forming dies, or piercing or work-supporting means at adjacent ends adapted to support a work-piece therebetween, means for externally 25 cooling said work-supporting heads, and means for internally cooling said piercing or work-supporting axles.
67. In an apparatus or mill for rolling or forming car wheels or other circular bodies, 30 the combination with a support, of a pair of work-supporting heads arranged in alignment on said support, an axle rotatable in each of said heads, said axles having piercing or work-supporting means at adjacent 35 ends adapted to support a work-piece therebetween, means for feeding a cooling medium to said heads and causing the same to flow in contact with the sides thereof, means for internally cooling said axles, and 40 a power or pressure device or devices to move said work-supporting heads toward and from each other, or together simultaneously in the same direction.
68. In an apparatus or mill for rolling or 45 forming car wheels or other circular bodies, a piercing or dishing or work-supporting head having a longitudinal bore formed therein, a hollow piercing or dishing or work-supporting axle rotatable in said bore, 50 and means for leading a cooling medium to the exterior of said head and to the interior of said axle.
69. In an apparatus or mill for rolling or 55 forming car wheels or other circular bodies, a pair of aligned work-supporting axles, each of said axles having a liquid or cooling medium receiving space therein, and means for feeding a cooling medium to said space.
70. In an apparatus or mill for rolling or 60 forming car wheels or other circular bodies, a pair of aligned work-supporting axles having piercers or work-supporting centers or work-supporting means at adjacent ends adapted to receive a work-piece therebe- 65 tween, each axle having a hollow space at said adjacent ends, and means for conducting a cooling medium to said hollow spaces.
71. In an apparatus or mill of the kind, described, a pair of aligned work-supporting heads, each having a longitudinal bore formed therein, a hollow or partly hollow work-supporting axle rotatable in each of said bores, and means for leading a cooling agent to the exterior of said heads and to the interior of said axles. 75
72. In an apparatus or mill of the kind described, a pair of aligned work-supporting heads longitudinally movable, each having a longitudinal bore formed therein, a hollow or partly hollow piercing or work-supporting means rotatable in each of said bores, and means for leading a cooling agent to the exterior of said heads and to the interior of said hollow piercing or work-supporting means. 80
73. In an apparatus or mill for rolling or forming car wheels or other circular bodies, a pair of aligned work-supporting heads, each having a longitudinal bore formed therein, a work-supporting axle rotatable in each of said bores and extending from opposite ends of the same, piercing or work-supporting means at one of the extending ends of said axles adapted to engage opposite sides of a work-piece, a thrust bearing 95 to receive the pressure of said axles when forcibly applying them with their piercing or work-supporting means to the work-piece, and means for internally cooling said axles at the ends having said piercers or work- 100 supporting means thereon.
74. In an apparatus or mill for rolling or forming car wheels or other circular bodies, the combination with a support having spaced and aligned guides, a work-supporting head longitudinally movable in each of said guides and having a longitudinal bore therein, a hollow work-supporting axle rotatable in each of said bores, means for leading a cooling medium to the exterior of said 105 heads, and means for leading a cooling medium to the interior of said hollow axles.
75. In an apparatus or mill for rolling or forming car wheels or other circular bodies, the combination with a support having a 110 guide, a work-supporting head longitudinally movable in said guide and having a longitudinal bore therein, a power or pressure device connected with said head for moving the same longitudinally, a hollow work-supporting axle rotatable in said bore, means for leading a cooling agent to the exterior of said head, and means for leading a cooling agent to the interior of said axle. 115
76. In an apparatus or mill for rolling or forming car wheels or other circular bodies, a pair of aligned work-supporting axles having female centers or forming dies at adja- 120 125

cent ends for centrally supporting a work-piece at opposite sides, power or pressure means operatively connected to each work-supporting axle for moving said axles longitudinally in the same direction when dishing said work-piece and for moving said axles toward each other or moving one of said axles toward the other for forcing said centers or forming dies over the hub or center portion of the work-piece for compressing the hub to make its outer diameter and the diameter of its bore smaller, rolls adapted to act against the work-piece to form or roll the same as and where desired and to laterally support and retain the marginal or peripheral portion of the work-piece while moving said axles with the center or hub portion of the work-piece together in the same direction to dish the work-piece, and means for partly cooling or taking away part of the heat from the center or supporting portion of the work-piece engaged by said centers or forming dies.

77. In an apparatus or mill for rolling or forming car wheels or other circular bodies, a work-supporting head having an opening extending transversely through its upper end, and a bore arranged lengthwise in a plane beneath said opening, a work-supporting axle rotatable in said bore, plates secured to opposite sides of the head to close said opening, means to supply a cooling medium to said closed opening, and means to permit the cooling medium to escape from said closed opening and flow in contact with the sides of the work-supporting head.

78. In an apparatus or mill for rolling or forming car wheels or other circular bodies, a work-supporting head having an elongated opening arranged through the upper end of said head, a work-supporting axle journaled in said head in a plane beneath said opening, said head being reduced in thickness directly beneath said opening, plates applied to the sides of said head to close the sides of the said opening and form a chamber, the lower ends of the plates being arranged at the reduced portion of said head to provide escape passages for said chamber, and means for feeding a cooling medium to said cham-

ber, said escape passages permitting the cooling medium to flow downwardly in contact with the sides of said head.

79. In an apparatus or mill for rolling or forming car wheels or other circular bodies, a work-supporting head having a longitudinal bore therein and a reservoir or chamber for a cooling medium above said bore, said reservoir or chamber being provided with an inlet for the cooling medium and with an outlet or outlets to permit the cooling medium to escape therefrom and flow downward in contact with the side or sides of said head.

80. In an apparatus or mill for rolling or forming car wheels or other circular bodies, a work-supporting head having a longitudinal bore therein and a reservoir or chamber for a cooling medium above said bore, a hollow or partly hollow axle or supporting means rotatable in said bore, said reservoir or chamber being provided with an inlet for the cooling medium and with an outlet or outlets to permit the cooling medium to escape therefrom and flow downward in contact with the side or sides of said head, and means for leading a cooling medium to and from the interior of said axle.

81. In an apparatus or mill for rolling or forming car wheels or other circular bodies, a work-supporting head having a longitudinal bore therein and a reservoir or chamber for a cooling medium above said bore, said reservoir or chamber being provided with an inlet for the cooling medium and with outlets to permit the escape of the cooling medium therefrom so that it may flow downwardly in contact with the sides of said head, ledges at opposite sides of the head in a plane beneath the longitudinal bore, plates secured to the ledges to form troughs to receive the cooling medium after flowing in contact with the sides of the head and an outlet in communication with said troughs.

In testimony whereof, I have hereunto set my hand.

LOUIS F. DIETER.
